MOTOR VEHICLE LAMP LENS

David R. Holls, Bloomfield Hills, Mich., assignor to General Motors Corporation, Detroit, Mich., a corporation of Delaware

Filed Oct. 18, 1967, Ser. No. 9,039

Term of patent 7 years

(Cl. D48—32)

FIGURE 1 is a front elevational view of a motor vehicle lamp lens showing my new design, the faceted lens surface being fragmentarily shown in the outer area for convenience of illustration, it being understood that the faceted surface appears throughout said area;

FIGURE 2 is a view taken along line 2—2 of FIGURE 1;

FIGURE 3 is a view taken along line 3—3 of FIGURE 1; and

FIGURE 4 is a view taken along line 4—4 of FIGURE 1.

I claim:

The ornamental design for a motor vehicle lamp lens, substantially as shown.
